COMBINATION ASH TRAY, MATCH HOLDER,
ETC.

Percy F. Dorsett, San Jose, Calif.

Application September 23, 1940, Serial No. 357,986

3 Claims. (Cl. 211—86)

This invention relates to combination ash trays, and more particularly to those in which the ash receptacle is combined with a support for a glass and holder for some article such as a deck of cards.

In devices of this type the primary features to be considered are simplicity of construction, economy, rigidity and stability. I realize that ash trays which incorporate other articles in the same structure have been developed before, and provided these features in varying degrees but, so far as I am aware, no one has as yet produced a device having the specific advantageous combination and arrangement of parts of that embodied in my invention.

The object of this invention is a structure conveniently combining an ash tray, glass holder, and article holder.

Another object is such a structure which may be conveniently attached to the edge of a table.

Another object is rigidity and stability in the arrangement of the various parts of such a structure.

Still another object is to produce such an article by utilizing the minimum number of parts and maximum economy of manufacture.

These and other objects may be accomplished by my invention which embodies among its features a wire frame having an upper, horizontal portion to form the periphery of a glass holder resting on the upper surface of the table, a vertical portion engaging the side surface of the edge of the table, an ash tray soldered to this portion, a horizontally extending clamp portion extending under and clamping the table edge, an extension on the vertical portion extending downwardly and bent horizontally under the ash tray to form an article holder.

Other objects and features may become evident from the following description when taken in connection with the accompanying drawing in which:

Figure 1 is a top plan view of my device in position on the edge of a table.

Figure 2 is a cross-section taken on line 2—2 of Figure 1, and

Figure 3 is a bottom plan view of my device.

Referring to the drawing in detail, the upper portion 10 of the wire frame is formed into a loop, as may be seen in Figure 1, which forms the periphery of a glass-holder 11. The ends of this wire loop are bent down as at 12 to form spaced vertical members, which engage the side surface of the table edge. Soldered to these vertical members 12 is an ash receptacle 13 of con-

ventional flat-sided oval construction as shown and carrying a suitable cigar holder 14 on its upper edge. The vertical members 12, at approximately the same level with the bottom of the ash receptacle 13, and at the proper level to engage the bottom of the table edge, are formed into double-strand horizontally extending clamping fingers 15 which clamp the bottom of the table edge to hold the device in position. Below these fingers the vertical portions 12 have extensions 16 which extend downwardly a short distance and then are bent over to horizontal position to form a closed rectangular article support 17, under the ash receptacle.

15 To provide the table-protecting surface 11 for the glass-holder 10, I utilize a circular plate of sheet metal having a strip 18 extending therefrom. The circular portion is soldered to the bottom of the loop 10 to form surface 11 and the strip, where the vertical portions 12 are formed, is bent upwardly at 19, then forwardly at 20, downwardly at 21 and backwardly at 22 to where it is secured at 23 under the strip 18. By this means I form over the ash receptacle a convenient matchbox holder as shown generally at 24 in Figure 1.

In operation the device may be securely attached to the edge of the table by means of the clamping action between fingers 15 and loop 10. 30 Then the surface 11 may be used to hold a glass and, at the same time, the ash tray 13 can be used together with the match-box holder 24, and the lower bracket 17 may be used to support a deck of cards or other article. Although a preferred embodiment of my invention is described herein I do not wish to be limited thereto but only by the scope of the appended claims.

What is claimed is:

1. In a device of the class described, an attachment for the edge of a table comprising a wire having an upper portion having secured thereto a metal disc adapted to rest upon the surface of the table and form a tumbler support, a vertical portion adapted to engage the edge of the table and have an ash receptacle attached thereto, a clamping finger extending horizontally from the vertical portion and positioned to engage and press against the bottom of the table, and a vertical portion extending below this finger and bent in the opposite direction from the finger horizontally to form an article support.
2. In a device of the class described, an attachment for the edge of a table comprising a wire with a looped upper portion adapted to overlie the surface of the table, the ends of the loop

being bent down into vertical strands contacting the edge of the table, an ash receptacle attached to said strands, said strands being formed, intermediate their length, into clamping fingers positioned to contact and press against the under side of the table edge, the lower ends of said strands extending vertically and then bent horizontally in the opposite direction from the fingers and joined to form a rectangular shaped article support.

3. In a device of the class described, an attachment for the edge of a table comprising a wire with a looped upper portion, a sheet metal

plate attached to and under this looped portion and forming a tumbler support, the ends of the loop being bent down into vertical strands contacting the edge of the table, said strands being formed, intermediate their length, into clamping fingers positioned to contact and press against the under side of the table edge, the lower ends of the strands extending vertically and then bent horizontally in the opposite direction from the fingers and joined to form a rectangular shaped article support.
